UNITED STATES PATENT OFFICE.

EDITH L. TIBBS, OF GREENVILLE, SOUTH CAROLINA.

FIRE-ALARM.

1,271,806.

Specification of Letters Patent.

Patented July 9, 1918.

Application filed June 12, 1916. Serial No. 103,221.

To all whom it may concern:

Be it known that I, EDITH L. TIBBS, a citizen of the United States, residing at Greenville, in the county of Greenville, 5 State of South Carolina, have invented certain new and useful Improvements in Fire-Alarms; and I do hereby declare the following to be a full, clear, and exact description of the invention, such as will enable 10 others skilled in the art to which it appertains to make and use the same.

This invention relates to the class of fire alarms, and has particular reference to a fire signal which is thermally operated to 15 close an electric circuit which includes the alarm.

The primary object of my invention is to provide a fire alarm which may be installed in localities in which fire is liable to occur 20 and is so arranged that the heat of a fire will be a prime factor in closing an electrical circuit in which is included an audible or a visible signal located at a suitable point of observation.

25 It is also an object of the present invention to provide a fire alarm apparatus which is adapted to be installed as a local signaling apparatus and which may be arranged to transmit a signal from various points in 30 a residence, or other building, the circuit closing apparatus being thermally controlled by the explosion of a suitable explosive material.

It is likewise an object of the present invention 35 to construct a suitable thermally controlled circuit closing device for use in electric signaling apparatus for indicating the presence of fire, in which the parts are few in number, and positive in action, the 40 apparatus being also capable of being quickly charged in order to place it in condition for further use.

With the above objects, and others in view, as will hereinafter appear, my invention 45 will now be fully set forth and described, reference being had to the accompanying drawings.

In said drawings:

Figure 1 is a side elevation of the circuit 50 closing apparatus which forms the subject matter of my invention,

Fig. 2 is an end elevation thereof,

Fig. 3 is a sectional view on the line 3—3 of Fig. 2,

55 Fig. 4 is a diagrammatic showing of the

electrical circuit which includes the apparatus of my invention,

Fig. 5 is a sectional view on the line 5—5 of Fig. 1,

Fig. 6 is a perspective view of a section 60 of a conduit employed in my invention, and

Fig. 7 is a plan view of an elbow section used with said conduit.

Referring more particularly to said drawings, 1 indicates a dome-like housing of 65 any suitable material, which is provided around its peripheral edge with the horizontally extending feet 2 by means of which the housing may be secured to the wall, a suitable base, or other surface. Said housing 1 incloses a bracket 3, within which a cartridge 4 is supported, said carriage being vertically supported so that the open top thereof extends a short distance above the bracket 3. Said cartridge 4 is formed 70 of a material suitable for containing an explosive and adapted to have the latter fulminated therein. The cartridge 4 is closed by a cap 5. Said cap 5 is formed of a suitable metal, as soft lead which may be renewed and is provided at its center with a reduced circular section 6. The reduced section 6 is scored around its edge so as to be bodily separable from the cap. Said cap 75 or cover 5 is secured to the cartridge 4 so as to compress within the cartridge 4 the coil spring 7 which normally rests between the bottom of the cartridge 4 and said cap 5, the upper end of the spring resting in the recess formed by the reduced portion 6. 80 Mounted at an exterior point adjacent the dome 1 is a base plate 8 carrying a standard 9, of which the upper end is shaped as at 10 to form a fulcrum for a rock lever 11, one end of said rock lever 11 extending 85 through a slot 12 formed in the side of the dome 1 and having an overhanging arm 13 which overlies the cap section 6 and the cartridge 4. The free end of the arm 13 90 supports a plate 14 which overhangs the cap 6, said plate 14 having a depending flange 15 which prevents the cap section 6 95 and the spring 7 from being thrown to one side when an explosion occurs in the cartridge 4. The opposite end of the lever 11 is provided with a weighted knob or 100 knocker 16 which overlies the button 17 of a suitable electrical push button switch 18. Said switch 18 is located in a suitable electrical circuit (Fig. 4) which contains visible 105

110

and audible signals, such as the bell 19 and the annunciator 20, said switch 18 being connected by a conductor *a*, to a current source *b* which is connected by the wire *c* 5 to an annunciator of conventional type, the conductor *d* completing the circuit back to the switch 18.

The cartridge 4 is provided, adjacent its lower end as indicated in Fig. 3, with a plurality of tubular outlets 21, said outlets providing a means for introducing a corresponding plurality of fuses 22 of any well known construction into the bottom of the cartridge 4. Said fuses may be secured to 15 the walls or other back ground and spread in various directions from the cartridge 4, so that fire at any one of the various points in a room to which the fuses are conducted will ignite the fuse at the danger point 20 which will then explode the cartridge. In order to protect the fuses 22 I provide a sectional conduit such as is illustrated in Figs. 6 and 7. Said conduit consists of a substantially semi-cylindrical tubing 23 25 which is perforated throughout its length to permit the access of air to the interior of the tubing.

In Fig. 6 is shown a section of straight tubing, one end of which may be closed as at 30 24 to provide complete protection for the out-lying end of the fuse. Obviously, the intermediate sections of the tubing will be open at both ends. In Fig. 7, 25 indicates an elbow section which permits the proper dis- 35 position of a fuse around corners, or for otherwise varying the direction of the fuse from one danger point to another.

The operation of my improved apparatus is dependent upon the presence of fire or 40 excessive heat caused by fire at any danger point where the apparatus has been installed. As is obvious from the above de- 45 scription, the circuit closing device is located at a suitable central point in a room or any inclosure in which it may be desired to provide fire protection, and leading there-

from is the plurality of fuses 22. Said fuses 22 are distributed as completely as possible around the room, and are covered by means of the conduit sections 23 and 25. 50

In order to charge the cartridge 4, a suitable fulminate is loaded therein, so as to surround the spring 7, the spring 7 being then compressed and the cartridge 4 closed by the weighted cap 5. The arms of the lever 55 11 are so constructed as to be normally counter-balanced, the knob 16 being clear of the button 17 and the plate 14 freely overhanging the cap 5. When the explosive in the cartridge 4 is ignited as by the presence of heat in the immediate vicinity, or through the medium of one of the fuses 22, the reduced section 6 of the cap 5 will be blown against the plate 14, and the spring 7 will be permitted to expand, the combination of forces throwing the arm 13 of the lever upwardly and forcing the weighted knob 16 into contact with the button 17 of the switch 18 where it is held by spring 7. Obviously, the operation of the switch will 70 75 complete the circuit above described, and operate the signaling apparatus included therein.

What is claimed is:—

In a fire alarm signaling system, a pair 75 of contacts, a lever connected with one of the contacts for procuring engagement thereof, a cartridge casing arranged in opposition to said lever, an explosive charge 80 in said casing, an expansile spring in said casing, a cap for the end of the cartridge adjacent the lever and including a frangible portion engageable by the spring and adapted upon explosion of the charge to release the spring for engagement with the lever 85 and a fuse extending from the casing.

In testimony whereof, I affix my signature, in the presence of two witnesses.

MRS. EDITH L. TIBBS.
